UNITED STATES PATENT OFFICE.

HARLEY M. JOHNSON, OF MARSHALL, MICHIGAN.

IMPROVEMENT IN RIPPERS AND RAG-LOOPERS.

Specification forming part of Letters Patent No. **136,065**, dated February 18, 1873.

To all whom it may concern:

Be it known that I, HARLEY M. JOHNSON, of Marshall, county of Calhoun and State of Michigan, have invented certain new and useful Improvements in Combined Tool or Implement, of which the following is a specification:

The nature of my invention consists in combining a rag-looper, seam-ripper, button-hole cutter, and eraser in a single implement so as to form a handy and convenient instrument, adapted especially for ladies' use, as will be hereafter more fully set forth.

The accompanying drawing represents a side elevation of my invention.

a represents the handle, into which the blade *b* is screwed or fastened in any desirable manner, when the instrument is to be used for the purpose of ripping seams, cutting button-holes, or as an eraser; but as it is to be for rag-looper also, in which the handle is not wanted, a screw, *c*, is firmly secured to the end of the blade, so that it can be readily removed from the handle and screwed firmly to a table, window-casing, or any other suitable base. The point of the blade *b* is constructed with a cutting-edge, *d*, on the rounded side as far as the recess *e*, while the side *h* is dull for the purpose of forming a guide to the fingers of one hand, so as to lessen the liability to accident. The edge *d* is used for

cutting button-holes and erasing, while the blade is attached to the handle; but when removed from it and screwed in an upright or horizontal position to a suitable base, it is to be used as a rag-looper, as follows: The two ends of rags are overlapped, as shown, which allows the right hand or short end to be crossed over into the recess *e*, while the long end is drawn back over the point, thus passing the short or right-hand end through the incision, and forming a perfect loop. On the back of the blade is formed the projection *i*, the end of which is dull, but has a curved cutting-edge at the point *o*, and which forms the seam-ripper.

This implement is very convenient and handy in all households, and forms a very desirable part of every lady's work-box.

Having thus described my invention, what I claim as new, and desire to secure by Letters Patent, is—

The blade *b*, having the cutting-edges *d o*, projection *i*, and screw *c*, substantially as set forth.

In testimony that I claim the foregoing as my invention I hereunto affix my signature this 14th day of December, 1872.

HARLEY M. JOHNSON.
